UNITED STATES PATENT OFFICE.

JOSEPH S. JOHNSON, OF NEW YORK, N. Y.

AUTOMATIC DOOR OPENING OR CLOSING APPARATUS.

SPECIFICATION forming part of Letters Patent No. 705,355, dated July 22, 1902.

Application filed October 17, 1901. Serial No. 79,036. (No model.)

To all whom it may concern:

Be it known that I, JOSEPH S. JOHNSON, a citizen of the United States of America, and a resident of New York city, county and State 5 of New York, have invented certain new and useful Improvements in Automatic Door Opening or Closing Apparatus, of which the following is a specification.

My invention consists of improvements in 10 apparatus for automatically opening doors by the tread of one approaching the door and closing them by weights or springs, as hereinafter described, reference being made to the accompanying drawings, in which—

15 Figure 1 is a transverse vertical section of the body of a railroad-car, showing an elevation from the inside of the car of the doors of one end provided with automatic opening and closing apparatus in accordance with my 20 invention, the said section being taken on line 2 2 of Fig. 2. Fig. 2 is a vertical section on the line 1 1 of Fig. 1. Fig. 3 is a horizontal section on line 3 3 of Fig. 1. Fig. 4 is a horizontal section on the line 4 4 of Fig. 1.

25 The invention is designed chiefly for sliding doors, as *a*, and particularly such as are suspended from overhead rails *b* by trolley-wheels *c* and commonly used in railroad-cars and in other structures. The essential features of the invention are a pair of rods *b'*, jointed together at one end *d* and at the other end pivoted to the doors, respectively, as at 30 *e*, preferably in interior spaces of the doors, said rods constituting a "toggle-joint" device and adapted to thrust the doors apart when the joint *d* is brought into line with the pivots *e* and to allow the doors to close when said joint *d* is shifted away from said line in either direction. In this case the arrangement is 35 such that said joint shifts downward for the closing of the doors. For automatically shifting the said toggle-jointed rods to thrust the doors open a cord *f* is connected at *d* and passes over guide-pulleys *g*, *h*, and *i* to a drum *j*, located under the floor, so as to be wound thereon when the drum is properly turned, for which a cord or strap *k* is wound on a small axial stem *l* of the drum and connected with a bell-crank *m* as a means of multiplying the motion of the bell-crank, which is subject to the thrusts of pivoted treadles *n* each

side of the doors when these treadles are stepped on by persons passing through the doors. Over the doors spiral springs *o* are provided for automatically closing them, and 55 they also return the bell-crank *m* through the action of the toggle device, cord *f*, drum *j*, and a strap *k* to the normal position, thus raising the pedals *n* preparatory for reopening the doors. It is obvious that weights suitably suspended on pulleys may be used instead of springs for closing the doors, and where only a single door is to be operated one of the rods *b'* may be jointed to any fixed object. 60

Any suitable automatic latch device for holding the doors open may be employed when, as in the case of car-doors, many people pass out together, such latch to be released for allowing the doors to be closed by 70 the brakeman or other official.

What I claim as my invention is—

1. The combination with a sliding door, of a toggle-joint device for opening said door, foot-pedals and a bell-crank subject to the 75 tread of persons passing through the door, a motion-multiplying drum connected with said bell-crank, and a cord and guide-pulleys therefor, said cord connecting said drum and the toggle-joint device for operating it, and 80 means for automatically closing the door and resetting the pedals.

2. The combination with a pair of sliding doors, of a pair of toggle-joint rods respectively fulcrumed on the doors for opening 85 them, foot-pedals and a bell-crank subject to the tread of persons passing through the doors, a motion-multiplying drum connected with the bell-crank, a cord and guide-pulleys therefor, said cord connecting said drum and 90 toggle-joint device for operating it, and means for automatically closing the doors and resetting the pedals.

3. The combination with a pair of sliding doors, of a pair of toggle-joint rods respectively fulcrumed on the doors within interior spaces of the upper portions of said doors for opening them, foot-pedals and a bell-crank subject to the tread of persons passing through the doors, a motion-multiplying drum 95 connected with the bell-crank, a cord and guide-pulleys therefor, said cord connecting

said drum and toggle-jointed arms for operating them, and means for automatically closing the doors and resetting the pedals.

4. The combination with a pair of sliding doors, of a pair of toggle-joint rods respectively fulcrumed on the doors within interior spaces of the upper portions of said doors for opening them, foot-pedals and a bell-crank subject to the tread of persons passing through the doors, a motion-multiplying drum connected with the bell-crank, a cord and guide-pulleys therefor, said cord connecting

said drum and toggle-jointed arms for operating them, and means for automatically closing the doors and resetting the pedals, said means consisting of coiled springs located at the upper ends of the doors and suitably connected for closing them.

Signed at New York city this 30th day of September, 1901.

JOSEPH S. JOHNSON.
